DIVERTER SPOUT

William H. Armstrong, Bloomfield Hills, Mich., assignor
to Borg-Warner Corporation, a corporation of Illinois

Filed Sept. 8, 1965, Ser. No. 86,902

Term of patent 14 years
(Cl. D91—3)

FIG.1

FIG.2

FIG.4

FIG.3

FIGURE 1 is a top plan view of a diverter spout showing my new design;

FIGURE 2 is a side view of the diverter spout;

FIGURE 3 is a bottom view of the diverter spout; and
FIGURE 4 is a front view of the diverter spout.

The dominant features of my design reside in the portions shown in full lines.

I claim:

The ornamental design for a diverter spout, substantially as shown and described.
